TOOL FOR COUPLING HYDRAULIC HOSES

James B. Christensen, R.R. 1B, Spencer, Iowa

Filed Mar. 17, 1965, Ser. No. 84,320

Term of patent 14 years

(Cl. D54—13)

FIG. 1 is a perspective view showing the new design for my tool for coupling hydraulic hoses,

FIG. 2 is a side view thereof with hoses being coupled shown in broken line for illustration only,

FIG. 3 is a top view thereof,

FIG. 4 is a front view thereof, and

FIG. 5 is a bottom view thereof.

I claim:

The ornamental design for a tool for coupling hydraulic hoses, as shown and described.
